UNITED STATES PATENT OFFICE.

JOHN C. SHAMBOW, OF WOONSOCKET, RHODE ISLAND.

SHUTTLE.

1,257,750.

Specification of Letters Patent. Patented Feb. 26, 1918.

Application filed October 16, 1916. Serial No. 125,765.

To all whom it may concern:

Be it known that I, JOHN C. SHAMBOW, a citizen of the United States, residing at Woonsocket, county of Providence, State 5 of Rhode Island, have invented an Improvement in Shuttles, of which the following description, in connection with the accompanying drawing, is a specification, like characters on the drawing representing like parts.

10 This invention relates to an improvement in shuttles generally and is directed to a novel means for retaining a cop-tube, bobbin or similar filling carrier upon the usual blade or spindle which is pivotally mounted 15 in the shuttle body to be swung into or out of operative position. More specifically this invention relates to an improvement in that class of shuttles in which there is a spring-actuated catch automatically operable upon 20 movement of the spindle to lock the filling carrier on the spindle and to unlock the same therefrom.

The object of this invention is to improve upon the construction of shuttles having means for securing the filling carrier on 25 the shuttle spindle.

Other objects of the invention will more fully appear from the following description and accompanying drawings and will be 30 pointed out in the annexed claims.

In the accompanying drawings, there has been disclosed a structure designed to carry out the objects of the invention, but it is to be understood that the invention is not confined to the exact features shown, as various 35 changes may be made within its reasonable scope.

In the drawings:

Figure 1 is a longitudinal section through 40 the shuttle body showing the spindle in operative position;

Fig. 2 is a similar section showing the spindle in inoperative or elevated position;

Fig. 3 is a section on the line 3—3 of 45 Fig. 1;

Fig. 4 is a section on the line 4—4 of Fig. 2.

In this selected embodiment of this novel locking device here shown, the spindle 1 has 50 a head 2 pivotally mounted on the pin 3 in the shuttle body 4 and is therefore movable into and out of the normal operative position shown in Fig. 1. The shoulder 5 of the head 2 bears against the head 6 of a stud 55 yieldably carried by the coiled spring 7 in a

suitable recess in the shuttle body. While such spring means are shown, any of the types commonly employed to accomplish the retention of the spindle in either operative lowered position or inoperative elevated position may be employed. The filling carrier here disclosed consists of a cop 8 of the usual tubular type adapted to be axially carried on the spindle.

In this improved shuttle there is provided 65 a novel device consisting of a clamping means on opposed sides of the spindle, normally to clamp the cop 8 on the spindle and prevent movement of the cop while the spindle is in lowered or operative position. 70 Desirably such clamping means is carried by a supporting instrumentality movably mounted so that the clamping means may be co-operatively moved relatively to the spindle to effect the release of the cop when the 75 spindle is raised to inoperative position.

In this preferred embodiment such clamping means comprises a pair of opposed jaws 9, one being disposed on each side of the spindle 1. These jaws 9 are preferably 80 formed integrally with a supporting instrumentality such as a shank or base 10 having a tail 11 which has a sliding and guiding bearing on the boss 12 of the spindle head 2. This base 10 is substantially rigid 85 and has securely fastened thereto a stud 13 which is mounted to reciprocate in an aperture formed in the spindle head 2. The stud 13 terminates, at its end opposite to the base, in a head 14 and a helical spring 15 is positioned on the stud, one end bearing against the stud head 14 while the other end is seated in an enlarged portion of the aperture in the spindle head in which the stud 13 reciprocates. Such stud head actuation 90

is well-known in this art and need not be more specifically illustrated. When the spindle 1 is raised from the operative position disclosed in Fig. 1 to the inoperative position of Fig. 2, the head 14 of the base 100 stud 13 contacts with a member, such as a metallic staple 16 secured to the shuttle body, and effects a camming function therewith whereby the stud is depressed within the spindle against the tension of the spring 15 tending to retain the stud in normal elevated position. This depression of the stud 13 relatively to the spindle head 2 results in the similar movement of the base 10 with relation to the head and therefore of the op- 110

posed clamping jaws 9 with relation to the spindle 1. Such relative position of the jaws and spindle, when the spindle is in inoperative position, is shown in Fig. 4. In such position the cop or filling carrier may be readily placed upon the spindle in axial alinement therewith as is customary in this art. The return of the spindle to normal working position automatically releases the head 14 of the base stud 13 from any depressive contact with the staple 16. And, thus, the spindle-return automatically functions to raise the jaws relatively to the spindle into a vertical, axially transverse position and causes them tightly to embrace and clamp the sides of the filling carrier on the spindle.

This preferred form of clamping device is formed of a piece of metal providing the rigid shank piece or base 10, having an integral, guiding, tail piece 11 at its rear end, and a pair of integral wings or plates forming jaws 9 in substantially a U-shape at the forward end of the base-forming shank. Each plate or jaw 9 has a flared tip 17 to afford ease of filling carrier positioning and so that the jaws may readily ride up the presented sides of such carrier upon the axially transverse movement of the jaws with relation to the spindle. Preferably, further, each jaw has its median vertical portion 18 stamped inwardly toward the spindle, as shown in Figs. 3 and 4. This affords a greater constriction of the space comprehended between the jaw members and assures a smooth traverse of the jaws over the sides of the filling carrier into final clamped position. When the spindle is returned to operative position, the filling carrier is securely clamped against movement on the spindle. As the spindle is manually downwardly pushed from the inoperative position of Fig. 1, the tensioned spring 7 causes the spindle to pivot toward operative position. As the spring often does not turn the spindle completely into operative axial alinement with the shuttle body, it is necessary manually to push it down and means are provided in this embodiment to assure the assumption of operative axial alinement of the spindle upon such manipulation. To this end, a stop, such as a pin 19, is positioned transversely the usual opening in the shuttle bottom. The underface of the base 10 of the cop-gripping jaws carried by the spindle abuts against the pin 19 and, not only thereby assures the proper spindle positioning, but also functions to prevent release, due to accidental depression of the stud head 14 as the base 10 is held against downward movement.

This novel device achieves the secure retention of the filling carrier on the shuttle spindle under working conditions and yet assures the facile, automatic release of the

filling carrier when the spindle is raised. This structure here disclosed is simple, certain in operation, inexpensively and easily produced and is durable and efficient.

It is to be understood that the construction disclosed herein is illustrative but not restrictive and that the same may be modified within the meaning and scope of the claims which follow.

Having thus described my invention, what I claim as new and desire to secure by Letters Patent is:

1. In a shuttle, the combination of a spindle pivotally mounted in the shuttle body and adapted axially to receive a filling carrier, clamping means on opposed sides of the spindle yieldably to clamp a filling carrier thereon when the spindle is in operative position, and means for movably mounting said clamping means so that the carrier may be automatically released on raising of the spindle to inoperative position.

2. In a shuttle, the combination of a spindle pivotally mounted in the shuttle body and adapted axially to receive a filling carrier, co-operative clamping means on opposed sides of the spindle yieldably to clamp a filling carrier thereon when the spindle is in operative position, a rigid shank member yieldably mounted to reciprocate in the spindle and carrying said clamping means whereby the filling carrier may be automatically released on raising of the spindle to inoperative position.

3. In a shuttle, the combination of a spindle pivotally mounted in the shuttle body and adapted axially to receive a filling carrier, members on opposed sides of the spindle to clamp said filling carrier thereon when the spindle is in operative position, means to lock said opposed clamping members against movement when the spindle is in said position, and means movably to mount the said clamping members on the pivoted spindle so as to have movement relative thereto whereby, upon movement of the spindle to inoperative position, the filling carrier is released by the opposed clamping members.

4. In a shuttle, the combination of a spindle pivotally mounted in the shuttle body and adapted axially to receive a filling carrier, members on opposed sides of the spindle to clamp said filling carrier thereto when the spindle is in operative position, means to lock said clamping members when the spindle is in said position, a supporting instrumentality for said opposed clamping members, means for movably mounting said instrumentality whereby, upon raising of the spindle to inoperative position, the opposed clamping means are automatically unlocked and the clamping members are automatically moved relatively to the spindle and the filling carrier released.

5. In a shuttle, the combination of a spindle having its head pivotally mounted in the shuttle body and adapted axially to receive a filling carrier; a rigid shank member 5 yieldably mounted to reciprocate in said head; a pair of plate members on said shank extending transversely to the spindle axis, one on each side thereof; and means on the plate faces adjacent the spindle to engage 10 and clamp said filling carrier upon movement of said shank member.

6. In a shuttle, the combination of a spindle having its head pivotally mounted in the

shuttle body and adapted axially to receive a filling carrier; a rigid shank member 15 yieldably mounted to reciprocate in said head; and a pair of plate members provided on said shank extending transversely to the spindle axis, one on each side thereof, each of said plate members having an inwardly 20 projecting median portion affording opposed gripping surfaces of an area sufficient firmly to grip the filling carrier.

In testimony whereof, I have signed my name to this specification.

JOHN C. SHAMBOW.
